Primary Examiner — George A Bugg*Assistant Examiner* — Jessica A Junkins(74) *Attorney, Agent, or Firm* — Hawaii Patent Services; Nathaniel K. Fedde; Kenton N. Fedde(57) **CLAIM**

The ornamental design for a key ring, as shown and described.

DESCRIPTION

FIG. 1 is a front, left, top perspective view of a key ring, showing my new design;

FIG. 2 is a rear, right, bottom perspective view thereof;

FIG. 3 is a rear, right perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is an enlarged view of detail 10 in FIG. 1;

FIG. 11 is an enlarged view of detail 11 in FIG. 2;

FIG. 12 is an enlarged view of detail 12 in FIG. 3; and,

FIG. 13 is an enlarged view of detail 13 in FIG. 6.

The dash-dot-dash broken lines are for notating enlarged views and form no part of the claimed design.

1 Claim, 11 Drawing Sheets(56)
